UNITED STATES PATENT OFFICE

J. ADDISON CROWELL, OF WALLKILL, NEW YORK, ASSIGNOR TO JAMES B. CROWELL & SON, OF WALLKILL, NEW YORK, A CORPORATION OF NEW YORK

BRICK MOLD

Application filed April 13, 1929. Serial No. 354,882.

The present invention relates to brick molds, and more particularly to a novel and improved brick mold for use in the manufacture of brick by the "soft mud" process" wherein clay material is forced through a die into a set of molds. These molds are principally constructed of wood, and are subjected to considerable pressure when the clay is forced out of a brick machine or press and 10 into the molds.

In the manufacture of brick by the use of said molds, either hand molds or such molds as are used in the present high speed and high pressure automatic brick machines, it 15 is necessary to have vents along the bottom of each mold for each brick to permit the air to be forced out of the mold as the clay is forced in, and to permit the clay—in a plastic condition—to flow fully into and completely 20 fill the mold, particularly at the ends, corners, and sides of the bottom. Such molds, however, must be made of considerable strength to withstand the pressure and beatings, and the vents as heretofore utilized were 25 unsatisfactory because of necessarily weakening the mold structure, and also forming "fins" or the like on the brick, and often-times choking up.

A further difficulty with prior vents in 30 molds has been that, due to the constant wetting and drying of the molds, and the consequent swelling and shrinking of the wood of the mold, the vents were constantly varying in size, thus preventing proper functioning of the mold. In my present invention I have devised a mold structure and vent which gives great and increased strength, and which insures the complete filling of corners, ends and sides, which insures an ample vent opening, and which furthermore insures a vent opening of constant size, irrespective of the condition of the wood of the mold, whether 35 wet or dry.

My novel mold will enable stiffer and better clay material to be put into the molds than has heretofore been possible.

The advantages of utilizing a stiffer clay will be instantly apparent to those skilled in the art, as the resulting brick stand up better, prevent deformation, dry quicker, and

burn more evenly and uniformly, thus improving the entire manufacture of the brick from the pug mill to the kiln. The advantages of providing unvarying vent openings will also be apparent to those skilled in the art. 55

In carrying out my present invention, I provide metallic strips or straps across the inner bottom edges of the mold panels, in such manner that at least one side of each vent opening will be defined by this metal strip. If desired, the strips may be provided with openings therethrough adapted to register with the vent openings cut in the bottom panels, in which event all sides of the vent openings would be defined by the metal of the strips. Thus, the swelling or shrinking of the wood of the mold will have no effect on the size of the vent opening, which will remain constant in size whether the mold is 60 dry or whether it is subjected to long and continuous moisture or wetting. 65

These metal strips are sunk in the wood of the panel in order to be flush with the inner bottom surface, and thus will not mar or injure the brick formed in the molds in any way. The ends and outer edge of each strip, also, will be flush with the ends and outer edge of the mold panels, thus enabling the panel to retain the same size and shape as 70 heretofore. 75

The above and other features and objects of the invention, details of construction, combinations of parts and advantages, will be hereinafter more fully pointed out, described 80 and claimed. 85

Referring to the drawings, illustrating a preferred embodiment of the invention,

Fig. 1 is a top plan view of a ten brick mold 90 constructed according to my present invention;

Fig. 2 is a vertical sectional view, on an enlarged scale and in perspective, on the line 2—2 of Fig. 1;

Fig. 3 is a perspective view of one of the mold backs or panels;

Fig. 4 is a cross-sectional view illustrating a slightly modified type of metallic vent strip; and

Fig. 5 is a perspective view of one of the panels utilized in the mold of Fig. 4.

Referring now to the drawings, for a particular description of the invention, it will be appreciated that the brick molds utilized in carrying out my invention may be of any suitable or desired number or size of brick. The invention may be embodied equally well in a hand sized mold for forming one, two or more 10 brick for hand dumping, handling and use, or in the present 6, 7, 8 or 10 brick and more, for use in the modern high speed or automatic brick machines and presses. As herein illustrated, a ten brick mold is shown, such 15 as is used in the present high speed or so-called automatic brick making machines, the mold illustrated comprising end blocks 1, sides 2, 2, partitions 3, 3, and the bottom panels 4.

20 These portions are constructed of wood, and are dovetailed together, fastened in various ways, and usually bound with iron straps 5 and 6. Heretofore it has been customary in mold construction of this type to either 25 make the panels 4 slightly spaced from the partitions 3, leaving a thin narrow vent or space between each panel edge and the adjacent side of the partition, leaving thin narrow vents through which the clay material 30 was forced, forming an objectionable burr or fin on the corner edge, and when subsequently broken off, this marred the brick. Another method has been to form recesses, at predetermined 35 distances from the edges of the panels 4, said recesses providing, when the panels are assembled in the mold, vents through which the air would be forced. The objection to this type of vents has been that when the wood of the mold was wet, a swelling thereof 40 would occur which would decrease the size of the vent opening and thus prevent proper functioning of the mold.

In carrying out my present invention, I provide, in each panel 4, and at predetermined 45 distances from the ends thereof, recesses 7, these recesses extending a desired distance into the wood of the panel and being beveled downwardly and outwardly. Then, along each side of the inner surface of the 50 panels 4, I apply metallic strips 8, secured to the panels 4 by screws 9 or the like. The recesses 7 are preferably slightly deeper than the width of the strips 8, thus forming vents 55 10, one side of each of which is defined by the edge of the strips 8. Thus, when the wood of the mold is wet and swells, the size of the openings or vents 10 will remain substantially unchanged, insuring constant proper functioning of the mold under all 60 conditions of moisture and dryness.

The outer edge and ends of the strips 8 will be flush with the outer edge and ends of the panels 4, and the said strips 8 will be set in the wood of the panels 4 flush with the 65 inner surface thereof, as clearly illustrated

in the drawings. Thus the size of the panels 4 is exactly the same as if made entirely of wood. These metallic strips 8 also will greatly reinforce and strengthen the said panels 4, and thus will greatly strengthen the 70 mold as a whole.

The number and size of the vents 10 may, of course, be varied depending on the character or quality of the clay material being utilized, but regardless of original size, these 75 vents will always remain constant and unvarying, being substantially unaffected by the "give and take" or swelling and shrinking of the wood of the mold. In this manner the vent openings 10 will always be proportional to the work and clay for which the mold is intended, larger openings being 80 suitable for higher speed operations and stiffer clay, or otherwise as desired or necessary.

In Figs. 4 and 5 I have illustrated a slight modification of the invention, wherein the iron strips 11 are secured to the panel 4 by screws 12 or the like, these strips being of greater width than the depth of the flared 85 openings 13, each strip 11 having vents 14 formed therein to register with said openings 13. Thus the vents 14 are positively unvarying and constant, without the slightest degree 90 of variation in size regardless of the conditions to which the mold is subjected. The strips 11 are set in the panels 4 in the same manner as the strips 8, flush with the inner surface of said panels, and flush with the ends and outer edges thereof. This slight modification is well within the scope and range 95 of the invention, as will be readily appreciated by those skilled in this art.

While I have necessarily described my present invention somewhat in detail, it will 100 be appreciated that I may vary the size, shape and arrangement of parts within reasonably wide limits without departing from the spirit of the invention.

105 My invention is further described and defined in the form of claim as follows:

In a multi-brick mold, a wooden bottom panel completely covering the bottom of each individual mold, said panel having recesses 110 cut inwardly from the sides thereof at predetermined spaced intervals, the inner walls of said recesses flaring from the upper surface of said bottom panel toward the center thereof, said panel having a recess extending longitudinally along the upper surface and at each side from end to end thereof, said first recesses projecting into the body of said panel beyond said second recesses, a metallic strip seated in each of said second recesses, 115 said strips being flush with the top, ends and sides of said panel, said strips traversing said first recesses and closing all but a relatively small amount thereof, said strips cooperating with said first recesses to form narrow vents 120 in the upper surface of said panel, one edge 125

of said strips forming one side of said vents and retaining said vents substantially constant in size, regardless of changing conditions of moisture or dryness, and means to 5 rigidly attach said strips to said panel in their recesses.

In testimony whereof, I have signed my name to this specification.

J. ADDISON CROWELL.
